UNITED STATES PATENT OFFICE.

CLYDE E. TRACEY, OF NEWARK, NEW JERSEY.

HAT.

Application filed August 28, 1926. Serial No. 132,116.

This invention has reference, generally, to improvements in women's hats; and the invention relates, more particularly, to adjustable hats provided with a novel construction of double brim to furnish an attractive two-color appearance.

This invention has for its principal object to provide a novel construction of hat comprising a lined main body or crown having a double discontinuous brim structure, the free ends of which may be so interconnected as to vary the head-size of the hat at will; and said double brim structure having a novel interconnecting means intermediate the opposed interior faces of its sections which tends to reinforce said sections against undue relative displacement when the hat is worn, while nevertheless permitting a limited displacement of one brim section relative to the other so that the desired two-color effect of the brim as a whole may be attained.

Other objects of this invention, not at this time more particularly enumerated, will be clearly understood from the following detailed description of the same.

The invention is clearly illustrated in the accompanying drawings, in which:—

Figure 1 is a side view of the novel construction of hat with the brim sections adjusted; Figure 2 is a bottom plan view of the same; and Figure 3 is a rear side view of the same.

Figure 4 is a fragmentary perspective view, with the brim sections separated to show the arrangement of the interconnecting reinforcing means thereof; Figure 5 is a fragmentary horizontal section, taken on line 5—5 in Figure 3; Figure 6 is a fragmentary detail vertical section, taken on line 6—6 in Figure 2, but with the brim sections turned down; Figure 6^A is a similar view with the brim sections turned up; and Figure 7 is a fragmentary detail rear face view, showing the discontinuous ends of said brim sections separated.

Similar characters of reference are employed in all of the hereinabove described views, to indicate corresponding parts.

Referring now to said drawings, the reference character 1 indicates the main body or crown of the hat, which may be suitably shaped and made of any desired material, but is preferably made of a pliable material such as cloth, felt or the like. Connected by stitching 2 to the free marginal edge of said body or crown 1 are the respective brim

sections adapted to overlie one another, and thus providing an outer brim section 3 and an inner brim section 4. Said brim sections are discontinuous and are of a length substantially exceeding the circumferential dimension of the marginal edge of the body or crown 1 to which they are attached, thus providing in connection with said brim section 3 overlapping free end portions 5 and 6 and with said brim section 4 overlapping free end portions 7 and 8. The attachment of said brim sections 3 and 4 to the body or crown 1 is such, that their overlapping end portions are positioned at the rear side of said body or crown, and are so related that the end portions 5 and 6 of the outer brim section 3 respectively overlie the end portions 7 and 8 of the inner brim section 4.

The stitching 2 by which the brim sections are connected to the body or crown 1 forms a seam, the ends of which terminate at the rear side of said body or crown short of the complete circumference of the latter, so as to leave free at such point a portion of the body or crown to form a contractable section 9.

The overlying brim sections 3 and 4, at a point adjacent to their free end portions 5 and 7 are provided with registering transverse slits forming an opening or slot 10. Said opening or slot is bounded with correspondingly slit reinforcing members 11, which are applied to the outer faces of the respective brim sections 3 and 4, and thereupon mutually secured to and with said brim sections by stitching 12; thus not only holding the slits of the overlying brim sections in registration, but reinforcing the opening or slot thus formed against undue enlargement by tearing of the surrounding material.

Preferably the hats are made up with the brim sections 3 and 4 respectively of contrasting color, and when shaped for wearing, said brim sections are upturned around the body or crown of the hat. In thus upturning the brim sections, the section 4 is exposed on the outside to overlie the upturned section 3. The turning movement thus imparted to the brim sections causes, however, a slight lateral displacement of one section relative to the other, so that the free marginal edge portion of the section 3 is slightly projected above the free edge of said section 4, and being of a contrasting color, produces an ornamental edging calculated to

greatly enhance the appearance and attractiveness of the hat. In order, however, to prevent undue relative displacement of said brim sections 3 and 4, when the same are upturned in the manner above described, there is provided intermediate the sections, and in connection with their interior meeting faces, a combined coupling and reenforcing member in the form of an intermediate web 13 of a length substantially corresponding to the length of the stitching or seam 2 which joins the brim sections to the body or crown 1. This web 13 is connected by stitching 14 at its opposite longitudinal edge portions respectively with the opposed meeting or interior faces of said brim sections 3 and 4 at points approximately midway between the attached edges and the free edges of said brim sections. When the brim sections 3 and 4 are upturned into normal position around the body or crown 1, the brim section 3 will be disposed within the brim section 4, and its upper free edge portion will project slightly higher than the upper free edge portion of the surrounding brim section 4, so as to furnish the desired ornamental edging of contrasting color bordering the latter section. When the brim sections are thus operatively arranged, the intermediate coupling and reenforcing web 13 serve to keep the brim sections symmetrical- 20 ly related in the above described relative arrangement, and the brim section 4 is coupled with the brim section 3 so as to be braced 25 or reenforced against sagging, wrinkling, bulging or other undesired displacement, all in a manner to be well understood from an inspection of Figure 6^A of the drawings.

When arranging the hat for wear, after 30 the brim sections 3 and 4 have been disposed in operative upturned arrangements as above described, the free end portions 6 and 8 of said brim sections are inserted through the opening or slot 10 of the opposed end portions 5 and 7, and drawn therethrough, until the contractable section 9 is sufficiently contracted to size the circumference of the body or crown 1 to accommodate the head of the wearer. The opening or slot 10, by reason of its reenforcements 11 is practically non-stretchable, and will therefore more or less compress the inserted end portions 6 and 8 so as to more or less bind the same against withdrawal, and at the same time 40 will effect the appearance of an ornamental bow or trimming element at the rear side of said body or crown. It is admissible, however, to positively secure the thus interrelated end portions 6-8 and 5-7 in any suitable manner if desired, as, e. g., by sewing, pinning or otherwise providing the desired fastening. Owing to the fact that the end portions 6 and 8 and 5 and 7 respectively overlie one another their contrasting colors 50 will be more or less exposed so as to thus

produce additional ornamental effect visible to an observer, as will readily be understood from an inspection of Figures 1, 2 and 3 of the drawings.

In order to provide stability to the body or crown 1 and to more or less support the same in desired shape or contour, there is provided an inner lining member 15 which is suitably secured to the inside marginal circumference of the body or crown so as to fit within and extend over the interior side of the same.

From the above description it will be evident that my present invention provides a novel hat structure for women's wear, which is durable and yet attractive, and one which is especially suitable for sports and informal wear.

Having thus described my present invention, I claim:—

1. A hat comprising a suitably shaped crown, a brim composed of two overlying sections of contrasting color secured to the margin of said crown and having free outer edges, said brim sections being adapted to be upturned around the exterior of said crown so that the free marginal edge of the inwardly disposed section is spaced and exposed above the free marginal edge of the outwardly disposed section, and a coupling reenforcing web secured by its longitudinal edges respectively with the opposed interior faces of said brim sections for the purposes described.

2. A hat comprising a suitably shaped crown of comparatively pliable material, a discontinuous brim composed of two overlying sections of contrasting color, said brim sections being secured to the margin of said crown but terminating short of the complete circumference thereof to provide a free contractable crown portion intermediate the ends of said brim, said brim sections being adapted to be upturned around the exterior of said crown so that the free marginal edge of the inwardly disposed section is spaced and exposed above the free marginal edge of the outwardly disposed section, a coupling reenforcing web secured by its longitudinal edges respectively with the opposed interior faces of said brim sections, and said brim sections having extended free end portions having means to interengage the same together so as to more or less contract said contractable crown portion intermediate the ends of said brim sections.

3. A hat comprising a suitably shaped crown of comparatively pliable material, a discontinuous brim composed of two overlying sections of contrasting color, said brim sections being secured to the margin of said crown but terminating short of the complete circumference thereof to provide a free contractable crown portion intermediate the ends of said brim, said brim sections being

adapted to be upturned around the exterior of said crown so that the free marginal edge of the inwardly disposed section is spaced and exposed above the free marginal edge 5 of the outwardly disposed section, a coupling reenforcing web secured by its longitudinal edges respectively with the opposed interior faces of said brim sections, said brim sections having extended free end portions, one 10 end of said overlying brim sections being provided with a transverse opening adjacent the point of juncture therewith of its free end portions, reenforcing means surrounding said opening, and said opening being adapted 15 to receive therethrough the free end portions of the opposite end of said overlying brim sections for the purposes described.

4. A hat comprising a suitably shaped crown provided with an inner lining, a dis-

continuous brim composed of two overlying sections of contrasting color secured to the margin of said crown and upturned around the exterior thereof so that the free marginal edge of the inwardly disposed section is spaced and exposed above the free marginal edge 20 of the outwardly disposed section, a coupling and reenforcing web secured by its longitudinal edges respectively with the opposed interior faces of said brim section substantially midway between the attached and 25 free edges of said sections, and mutually interengageable means at the ends of said brim sections relatively adjustable to vary the circumferential size of the crown.

In testimony that I claim the invention set 30 forth above I have hereunto set my hand this 23rd day of August, 1926.

CLYDE E. TRACEY.
